[57] **ABSTRACT**

A cemetery monument base is provided which is relatively inexpensive to produce, yet long lasting and impervious to the elements. The base includes an attractive, durable housing of stainless steel, or other non-corrosive materials, which jackets a heavy concrete core having several urn receiving cavities therein, and with a plurality of mounting brackets extending therefrom.

BASE FOR CEMETERY MONUMENTS WITH URN RECEIVING CAVITIES

Generally, the present invention relates to cemetery monument support bases, and more particularly to monument bases with receptacles therein for holding cremation urns.

In the past, cemetery monument bases have been provided, many of which were made from granite, marble, and other stone materials, being shaped with square corner edges which were susceptible to cracking and chipping over a period of years. With modern day lawn cutting equipment, it is difficult to cut around such conventional monument bases, often damaging the bases in the process. Furthermore, conventional monument bases are often unanchored and above the ground for the most part, rendering them vulnerable to damage or destruction by possible vandalism.

It is an object of the present invention to provide a cemetery monument base which is relatively simple and inexpensive to produce, yet is long lasting, functional, and of a durable construction.

Another object of the present invention is to provide a cemetery monument base which is comprised of a heavy core material surrounded by a stainless steel jacket which is attractive in appearance and impervious to the elements.

It is a further object of the present invention to provide a method of producing cemetery monument bases by pouring a hardenable material, such as concrete, into a surrounding stainless steel jacket and inserting several anchoring brackets into the material prior to hardening.

It is still another object of the present invention to provide a cemetery monument base having curved end portions which create a smooth outer surface not susceptible to cracking and chipping over a period of years.

Still another object of the present invention is to provide a monument base of heavy core construction which contains several urn receptacles therein which may be easily sealed from the elements or possible damage by vandalism.

It is another object of the present invention to provide a cemetery monument base which may be mounted either partially above or entirely below the ground and which is easily fastened between the foundation and the monument.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a perspective, phantom view of the monument base mounted underground and anchoring a ground level monument in place.

FIG. 2 is an exploded perspective view of the surrounding jacket and bracket assemblies.

FIG. 3 is a sectional view of the underground base shown in FIG. 1 with an urn inserted in one of the receptacles.

FIG. 4 is a sectional view along plane 4—4 shown in FIG. 1.

FIG. 5 is a perspective view of a second embodiment of the monument base extending partially above the

ground with the bottom fastened to an underground foundation.

FIG. 6 is a perspective view of the monument base shown in FIG. 5.

FIG. 7 is a sectional view of the above-ground monument base shown in FIG. 5.

Referring more specifically to FIG. 1, the monument base is indicated by the numeral 10, and secures a flat ground level monument 12 in place by way of a plurality of bolts 13 extending through flanges 14 of monument base 10. A pair of vertically extending urn cavities or receptacles 16 extend the entire height of monument base 10 to accept cremation urn 17, and are sealed from the outside by way of monument 12.

The monument base 10 is comprised of a core 18 which is made from a heavy hardenable material, such as concrete, surrounded by an outer jacket 20, preferably of stainless steel or similar materials. The outer surrounding jacket 20 may be formed from several pieces as shown in FIG. 2. A pair of upright semicylindrical end portions 28 are fastened to a pair of relatively flat side portions 30 by way of vertically extending flanges 32 adapted to abut each other and containing a plurality of apertures 34 which align with each other to accept bolts or similar fastening means. Several brackets 36 extend vertically along the inner surfaces of end portions 28 each including an upper horizontal flange 14 and a lower horizontal flange 38 extending outwardly from the curved end portions 28. If desired, the upper and lower edges of curved end portions 28 may include notches or slots 29, to accept the upper and lower horizontal flanges 14 and 38 respectively. This provides smooth upper and lower mounting surfaces and aids in the concrete pouring procedure hereinafter explained. The bottom of each flat side portion 30 includes an outwardly extending foundation flange 40 with holes 42 therein. Thus, monument base 10 may be anchored to a foundation of concrete, or similar material, by way of studs or bolts 24 which extend through flanges 38 and 40, as shown in FIG. 4.

The foundation may be in the form of a flat slab such as foundation 22 shown in FIGS. 3 and 4, or it may include a pair of receptacle extensions 44 as contained in foundation 46, shown in FIG. 7. Each receptacle extension 44 is adapted to align with urn receptacles 16 such that each urn is actually deposited in the extension 44 after passing through receptacle 16. This arrangement further insures that the cremation urn will not be harmed through vandalism or accidental damage to the monument.

Referring to FIGS. 5 and 6, it will be appreciated that the monument base may be partially elevated above the ground level to anchor the monument 48 in an elevated position wherein the edges 49 of monument 48 are substantially removed from the areas encountered by grass cutting equipment. It should also be noted that the jacket 50 of the monument base may be formed from a single piece, as more clearly shown in FIG. 6, rather than the four-piece construction illustrated in FIG. 2. The one-piece construction of jacket 50 provides a somewhat neater outward appearance and may be less expensive to produce, by such methods as welding, depending upon the number of units desired. Also, it is not essential that the foundation bracket 40, shown in

FIG. 2, be included in the one-piece construction where it is felt that lower flanges 38 will sufficiently anchor the base to the foundation. The one-piece construction may also include metal receptacle liners 53 connected to jacket 50 by way of metal top member 55.

The monument 48 is fastened to the base 10 by way of studs 51 which extend through upper flanges 14 and are held in position by nuts 52. It will be appreciated, that nuts 52 may be of a special configuration such that they may not be removed by standard tools, thus preventing the possibility of their removal by acts of vandalism. When desired, similar fastening means may be provided for foundation studs 24, to insure that the base may not be removed from the foundation.

The method of producing the monument base 10 is relatively simple and inexpensive. The outer monument jackets are preferably delivered from the factory to the customer prior to the addition of the heavy concrete core. This results in a substantial reduction in shipping costs compared with conventional bases, due to the reduced weight. In the disassembled condition, the multi-piece jacket construction requires less space for packing and shipping, thereby resulting in further cost savings. The one-piece jacket may be preferred where the customer does not desire to assemble the pieces in the field or prefers the smoother outward appearance. The multi-piece jacket is assembled by way of flanges 32 and is rested on a substantially flat mold surface which serves as the bottom of the mold into which a hardenable material, such as concrete, is poured. This flat mold surface should be of such a character that it will not adhere to the hardened material, such that the monument base may be easily lifted therefrom after hardening. Such mold surfaces are well known in the art and include such materials as oil treated plywood panels. As the pouring of the hardenable material is begun, elongated brackets 36 may be inserted into position to be held there by the weight of the material as the pouring process is continued. When the end portions 28 are notched to accept flanges 14 and 38, the bottom edges of each end portion 28 will form a neat seal with the flat mold surface, such that the concrete, or other hardenable material, will not leak through. When the notches are not provided, some suitable means of sealing the crack, such as a piece of sheet metal, may be used. After the material is allowed to harden, the monument base 10 is freed from the lower mold surface, and is ready for mounting to a foundation, as explained above. When it is desirable to form urn receptacles 16, an upper mold with receptacle forming extensions thereon is inserted over the top of the jacket prior to pouring. The mold extensions which form the receptacles may be of metal or other material which will not adhere to the concrete, such as those explained above. Preferably, the extensions of the upper mold are slightly tapered inwardly as they extend in the downward direction, to provide easier removal after the material has hardened. When using the one-piece construction with receptacle liners 53 and metal top 55, as shown in FIG. 7, the jacket is merely inverted prior to pouring, and no additional mold pieces are required.

It is appreciated, that a versatile, relatively simple, inexpensive monument base is provided which is practically indestructible and highly impervious to the elements over a period of years. The size and number of urn receptacles may be varied in the field by the use of various mold configurations inserted prior to pouring hardenable material. Furthermore, the over-all length of each multi-piece monument base may be varied in the field by the insertion of additional side portions 30 between end portions 28 prior to the pouring process. Thus, the multi-piece jacket construction permits a high degree of flexibility, relatively low cost and long life not provided by conventional manument base constructions. It is also appreciated, that when utilizing the unnotched end portions 28, the position and number of elongated brackets 36 may be varied in the field dependent upon the needs of the individual situation. It should be further noted that the completed monument base of the present invention may be utilized for purposes other than cemetery monuments. It is foreseeable that the base could be used as a time capsule base for building cornerstones or the such.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention.

What is claimed as new is as follows:

1. In combination with a cemetery monument, a base underlying and supporting said monument, said base comprising a heavy core of hardenable material, metal jacket means for molding and at least partially surrounding and embracing said heavy core, and bracket means fastening said core and jacket means to said monument, a cremation urn receiving cavity formed in said core, said cavity extending downwardly from an opening in said core abutting said monument such that said monument defines a top closure for said cavity, said cavity being surrounded on its sides by both said metal jacket means and a heavy thickness of said core to prevent unauthorized entry into said cavity due to vandalism, or the like.

2. The structure as set forth in claim 1 wherein said metal jacket means includes a metal liner around said urn cavity.

3. The combination set forth in claim 1 wherein said cavity is of generally cylindrical configuration together with a cremation urn of similar configuration disposed in said cavity.

4. The combination set forth in claim 1 together with a foundation underlying said base, said bracket means securing said base to said foundation.

5. The combination set forth in claim 4 wherein said bracket means includes a plurality of vertically elongated bracket members embedded in said core adjacent said metal jacket means each with a pair of offset flange portions extending horizontally outward at the opposite ends of said bracket member.
